UNITED STATES PATENT OFFICE.

WILLIAM ROBERTS, OF BARBERTON, OHIO, ASSIGNOR TO THE DIAMOND MATCH COMPANY, OF CHICAGO, ILLINOIS, A CORPORATION OF ILLINOIS.

MATCH-MACHINE.

1,236,764.

Specification of Letters Patent.

Patented Aug. 14, 1917.

Application filed March 30, 1917. Serial No. 158,504.

To all whom it may concern:

Be it known that I, WILLIAM ROBERTS, a citizen of the United States, and resident of Barberton, in the county of Summit and 5 State of Ohio, have invented certain new and useful Improvements in Match-Machines, of which the following is a specification.

This invention relates to that class of 10 match machines, termed "continuous machines," in which is employed an endless carrier by means of which splints, in separated rows, are transported through the match-making path, including a paraffin-15 applying station and a head composition applying station or stations.

The invention has particular reference to 20 mechanism whereby those parts of the splint carrier which are located immediately above the paraffin and composition stations can be positively lifted, and, at the same time, the machine can be stopped (although the composition-applying roller continues to rotate as usual,) thereby obviating any liability 25 of the carrier, with its depending splints, overrunning the respective stations when the machine is being thrown out of operation; and whereby, also, the starting of the machine and the lowering of the said parts of 30 the splint carrier can be simultaneously effected.

The present invention may be described 35 as a modification of or improvement upon the apparatus forming the subject of an application filed by Joseph C. Donnelly and myself on the 23d day of May 1916, under Serial No. 99,284, which apparatus employs raising and lowering mechanism for the splint carrier, brake means for the main 40 shaft of the match machine, plural cam mechanism, and connections operable thereby to throw off the power from the main shaft, apply the brake means, and actuate the first named mechanism to raise a part 45 or parts of the carrier; and the converse. According to my present invention, I dispense with the plural cam mechanism and its directly associated elements, and use in lieu thereof and for the same purpose, a 50 simplified construction and organization of mechanisms which will be hereinafter described and claimed.

In the drawings—

Figure 1 is a side elevation of a part of a 55 match machine embodying a form of my in-

vention; the parts being shown in their normal running position.

Fig. 2 is a plan, partly in section, of the improved mechanism, showing the motor, the power shaft of the match machine, and 60 associated elements.

Fig. 3 is a transverse vertical section, as on the line 3—3 of Fig. 2, showing the improved controlling mechanism.

Fig. 4 is a longitudinal vertical section, 65 as on the line 4—4 of Fig. 2, showing the brake and the actuating mechanism therefor.

Fig. 5 is a similar section through the main drive shaft and adjuncts, as on the 70 line 5—5 of Fig. 2.

Fig. 6 is a transverse section through the auxiliary shaft, the positively-driven gear hub thereon and the dog-actuated key for temporarily locking said hub to the shaft, 75 showing the shiftable abutment members so positioned that the forward member is engaged by the key-dog and the key accordingly set to release the gear from the said shaft.

Fig. 7 is a view similar to Fig. 6, but showing the abutment members shifted to the left (forwardly); the dog being positioned to lock the gear to the shaft. In this view dotted lines indicate the key and its 85 actuating dog in the positions which they are caused to assume by the engagement of the dog with the rearward abutment when the shaft has made a half rotation, thereby releasing the gear.

Fig. 8 is a sectional perspective view of the said gear, showing the internal construction of the hub.

Fig. 9 is a perspective view of a portion 95 of the auxiliary shaft with its key and dog carrying element; the key and dog and associated parts being illustrated as detached.

Fig. 10 is a detail perspective view of the crank disk and cam element for actuating the lifting and brake rods respectively, 100 showing the wrist pin connection for the lowering end of the lifting rod.

Fig. 11 is a skeleton perspective view showing the movable key and its associated devices, the brake and the operating mechanism therefor, and the manual shifting mechanism for determining the operative and inoperative conditions of the key and 105 brake controlling elements.

Fig. 12 is a transverse vertical section 110

through a part of the paraffin tank and the chain supporting and lifting frame.

Fig. 13 is a similar section through the chain supporting and lifting frame, and 5 associated parts adjacent the composition chest.

Referring to the drawings, 20 designates a part of the endless splint-carrier chain of a continuous match machine, which chain, in 10 the form illustrated, comprises a series of perforated plates linked together at their edges, and provided with marginal gear racks throughout the length of the chain. This chain is suitably supported and guided 15 throughout its circuit, and pairs of spaced power-driven gear wheels are arranged at intervals in the circuit, as indicated at 21, so as to mesh with the gear racks and impel the chain as usual. These wheels are oper- 20 atively connected through appropriate shafts and gearing with a drive pulley 22 which is loosely mounted on one end of the main shaft 23 of the match machine; a suitable clutch 24 being provided whereby the pul- 25 ley can be rendered fast or loose on the shaft as desired. When the pulley is loose the power is transmitted therefrom through the gearing to the carrier chain, without actuation of the main shaft of the match 30 machine, but when such pulley is clutched to the shaft, said shaft and the usual splint cutting and other mechanisms associated therewith are actuated concurrently with the splint carrier. The splints as rapidly 35 as they are produced are inserted into the successive rows of perforations of the chain plates and are thereby transported through the match making path. In this path are included the paraffin-containing tank 25 40 with the contents of which the traveling splints are treated, and also one or more composition applying structures (of which one is illustrated at 26) by means of which the composition for the ignitable bulbs or 45 "heads" is applied to the free ends of the splints after they leave the paraffin bath.

27 designates a power-driven shaft having its bearings in suitable standards on a base 28 in rear of the main shaft. This 50 shaft is conveniently driven from a suitable source of power, as, for example, an electric motor 29, the shaft of which is operatively connected with the shaft 27 through meshing gear wheels 30, 31 on the respective 55 shafts.

On the shaft 27 is mounted a pulley 32 which is connected with the pulley 22 on the shaft 23 of the match machine, by means of a belt 33. A suitable clutch is provided 60 whereby the pulley 32 may be locked or unlocked to or from its shaft as desired, said clutch including a member 34 slidingly keyed on the shaft 27.

35 designates a brake shoe positioned ad- 65 jacent the periphery of the pulley 22. This

shoe comprises a block of appropriate material seated in a socket in one arm of a lever 36 which is fulcrumed in a suitably-disposed bracket 37. The other arm of the lever is connected to a rearwardly-extending 70 brake-operating rod 38. A spring 39, encircling this rod and bearing against a shoulder 40 thereon and a lug 41 on the base for the bracket 37, tends normally to maintain the rod in brake-releasing position. 75 (See Figs. 2 and 4.) The rod 38 is pivotally connected with a depending crank arm 42 fast on one end of a rocker shaft 43 having its bearings in brackets 44 on the base-plate 28 adjacent the shaft 27; whereby 80 when the rocker-shaft is actuated as herein-after described, the crank lever is moved in a manner to pull the brake rod 38 and apply the brake to the periphery of the drive pulley 22.

85

45, 46 designate two carrier supporting frames pivotally mounted above and in close relation to the paraffin tank and the composition chest, respectively.

The free end of the frame 45 is connected 90 by means of a link 47 with a crank arm 48 which is carried by a shaft 49 having its bearings in appropriate brackets on the frame posts. The shaft 49 is also provided with a crank arm 50 which is connected by 95 means of a rod 51 with one arm of a crank lever 52 which is borne by a shaft 53 having its bearings in brackets on the frame posts adjacent the drive mechanism; the other arm of this lever being pivotally connected to a link or rod 54, by the vertical movement of which the crank and link connections are actuated to effect the raising or the lowering, as desired, of the frame 100 45 and the portion of the carrier supported 105 thereby.

100

The frame 46 is provided with the usual laterally-projecting anti-friction rollers 55, against each of which bears a sector cam 56 carried by a rocker-shaft 57 having its 110 bearings in brackets on the frame 58 of the composition structure, whereby when the shaft 57 is properly actuated the frame 46, with the proximate portion of the splint carrier, may be raised or lowered as desired. 115

The rocker shaft 57 is provided at each end with a crank arm 59 which is connected by means of a link 60 with a crank arm 61 on the end of an elevated rocker-shaft 62. This shaft extends from side to side 120 of the machine, and has its bearings in appropriate brackets on the frame posts. The shaft 62 is provided at each end with a lever 63 which is connected by means of parallel rods 64 with a similar lever 65 on a rock- 125 shaft 66 located above the drive mechanism, said shaft 66 having its bearings in brackets on the frame posts. On the shaft 66 is a crank-arm 67 which is connected to the upper end of the rod 54; whereby when the 130

latter rod is actuated as above mentioned, the rods 64 are moved longitudinally in opposite directions to each other so as to operate the sector cams 56 and thus raise or 5 lower the frame 46 as the movement of the rocker shaft 57 may dictate.

The rods 64 are preferably connected by supporting rock levers at various points throughout their length.

10 The mechanism above described, excepting as hereinafter particularly pointed out, is or may be similar in construction and operation to the corresponding mechanism illustrated in the application Serial No. 15 99,284 aforesaid.

10 Adjacent to and in parallelism with the shaft 27 is an auxiliary shaft 68 having its bearings in standards 69 on the base-plate 28. On the shaft 68 is loosely mounted a 20 spur wheel 70 of special construction which meshes with and is constantly driven by a pinion 71 on the shaft 27. The hub of the wheel 70 is mounted to turn on a bushing 72 which is fast on the shaft 68, said hub 25 being provided on its inner surface with a series of equally spaced recesses 73 which extend parallel to the axis of the hub and constitute, in effect, key ways.

The bushing has formed thereon at one 30 end a head 74 having a lateral extension 75 which is recessed, as at 76, adjacent the spur wheel, to provide a seat for a vibratory outwardly-projecting arm 77 constituting a dog. The inner end of this arm is pivoted 35 to the head of the bushing by means of an integral stud 78 on the arm. This end of the arm carries a key 79 which by actuation of the arm may be positioned to enter any of the key ways 73 in the hub of the spur 40 wheel and thus lock the latter to the auxiliary shaft, as will presently appear. In the present instance, the key 79 comprises a substantially semi-cylindrical member formed integral with the arm and its pivot stud. 45 This member is seated in a correspondingly formed recess 80 in the periphery of the bushing 72, the outer face of such member being rounded in conformity with the peripheral curvature of the hub, and the relative 50 positions of the parts being such that when the dog is in horizontal position such outer surface is flush with the periphery of the hub; or, in other words, the key 79 is confined within the recess of the hub. When 55 the dog is tilted on its axis from the horizontal position one edge of the key projects outwardly beyond the periphery of the hub. In the present instance such tilted position of the dog is effected by a spring 81 which, 60 being confined in a socket 82 in the extension 75, takes against the shouldered portion of a stem 83 which is pivoted to the dog so as to extend into the spring.

A simple and efficient means for actuating 65 the dog in order to move the key 79 into

locking and unlocking relation with the recessed hub of the spur wheel, at predetermined intervals, is as follows: 84, 85 designate two up-standing arms affixed at their lower ends to spaced rock-shafts 86 which are journaled in the standards 69. These arms embrace the shaft 68, and are pivotally connected at their upper ends by means of a link 87, so that they may be swung as a unit in order to move the arms toward and from the shaft in alternation. One of the arms, in the present instance the arm 85, terminates in a ball 88 which enters the slotted end of an arm 89 extending from the lever 90 the rearward arm of which is connected to the clutch member 34, whereby when said lever is operated to clutch the pulley 32 to the shaft 27 and thus start the match machine, the arms 84, 85 are swung rearward to the position indicated in Fig. 6, and when the said lever is actuated to unclutch the pulley from the shaft 27 and thus stop the match machine, the arms 84, 85 are swung forward to the position shown in Fig. 7. The arm 84 is provided with a lateral shouldered portion 91, which, when such arm is in its rearward position, overhangs the path of the outer end of the dog 77 and thus serves as an abutment therefor to move the dog to and maintain it in horizontal position against the pressure of the spring as indicated in Fig. 6. Thus the peripheral continuity of the bushing is uninterrupted by the key 79 and the spur wheel 70 is free to turn on the bushing. When, however, the arms 84, 85 are swung forwardly, as indicated in Fig. 7, the shoulder 91 of the arm 84 is removed from the outer end of the dog, whereupon as the wheel rotates one of its internal ways 73 immediately bridges the key recess of the bushing, and the spring 81, expanding, raises the dog and swings the key 79 into registry with the adjacent internal way of the gear hub. This done the spur wheel is keyed to the hub and the latter, together with the auxiliary shaft, is, perforce, positively turned by said spur wheel in the direction indicated by the arrow in Fig. 7. In a half rotation of the auxiliary shaft, the outer end of the dog abuts against a lateral shoulder 92 on the arm 85, thereby causing the dog to assume a horizontal or radial position, and disengaging the movable key 79 from the key-way in the hub of the spur wheel, as shown in dotted lines in Fig. 7. This spur wheel then freely rotates on the auxiliary shaft, as before. When the arms 84, 85 are swung to their previous or rearward position, the shoulder of the arm 85 is removed from the dog and the shoulder 91 of the arm 84 is again positioned in the rotary path of the dog. Thereupon the spring 81, expanding, tilts the dog and swings the key 79 into registry with the then adjacent key-way of the spur wheel hub. Thus such 130

wheel is keyed to the bushing and the latter, together with the auxiliary shaft, is positively turned by the spur wheel. In a half rotation of the auxiliary shaft the outer end 5 of the dog abuts against the shoulder 91 of the arm 84, which causes the arm to assume the horizontal or radial position shown in Fig. 6, thus disengaging the key 79 from the way in the hub of the spur wheel and permitting 10 the rotation of said wheel independently of the shaft.

In the present instance, the lever 90 is fulcrumed on a bracket 93 on a post 94 on the base plate, the forward arm of the lever 15 being connected by means of a link 95 to a crank arm 96 the hub of which is mounted to turn on a suitably-disposed frame post. To this hub is secured another crank arm 98 from which extends toward the front of the 20 machine a handle rod 99, by manipulating which the cranks may be turned, one way or the other as desired, in a manner to effect through the link and lever connections just described, the concurrent shifting of the 25 clutch member on the positively driven shaft 27 and the positioning of the coupled arms 84, 85. (See Fig. 11.)

The outer end of the auxiliary shaft has affixed thereto a disk 100 to one face of 30 which, eccentrically thereof, is pivotally connected the lower end of the link or rod 54 by means of a wrist pin 101, whereby during the rotation of said disk, by actuation of the shaft 68, said rod is raised or lowered, 35 thereby effecting the raising and permitting the lowering of the carrier in respect to the paraffin and composition tanks.

The disk 100 is equipped with a peripheral cam 102 against which bears a roller 40 103 on an up-projecting crank arm 104 fast on the rocker shaft 43 carrying the crank arm to which the brake rod 38 is connected, as above described. The cam is so formed and positioned in relation to the wrist pin 45 connection of the rod 54 with the disk, that when the rod is in its lowermost position (as indicated in Fig. 4) the roller 103 bears against the low portion of the cam and the brake is free from the pulley 22 on the shaft 50 of the match machine. At this stage the pulley 32 is clutched to the power driven shaft 27 and the arms 84, 85 are in the position shown in Fig. 6, the match machine thus being in operation and the auxiliary 55 shaft being idle. When, however, it is desired to stop the match machine, the handle rod is pulled forward, thereby unclutching the pulley 32 from the power-driven shaft 27, and shifting the arms 84, 85 to the rear- 60 ward position illustrated in Fig. 7. In this operation the spur wheel is instantly locked to the auxiliary shaft and the latter is, perforce, positively rotated. When the auxiliary shaft, together with the disk and cam 65 thereon, has made a half turn the spur wheel

is unlocked from the shaft as above mentioned. In the initial movement of the auxiliary shaft the rise of the cam depresses the crank arm 104 and effects the application of the brake to the pulley 22 so as to stop the 70 match machine; and in the continued movement of said shaft the disk lifts the rod 54 which, in turn, effects through the connections described the raising of the pivoted frames 45, 46 and the portions of the carrier 75 supported thereby above the paraffin tank and the composition chest (or chests) respectively.

When it is desired to start the match machine the handle rod is manipulated to clutch 80 the pulley 32 to the shaft 27 and to shift the arms 84, 85 to the position shown in Fig. 6, whereupon the spur wheel is locked to the auxiliary shaft and the latter is positively moved a half-turn, the disk in its travel 85 effecting the lowering of the splint carrier and the cam permitting the release of the brake, as previously described.

The shaft 27 preferably bears at or near one end a pulley 105 which is adapted to be 90 connected with the usual operating mechanism of the composition roller and adjuncts, in order that such roller may be continuously driven irrespective of the active or idle condition of the splint carrier.

It is to be understood that I do not limit my invention to the specific details of construction herein shown and described, as the mechanisms may be variously modified within the scope of the appended claims. 100

I claim—

1. In a match machine, the combination of a splint carrier, a vessel below the path of the carrier, a movable carrier-support adjacent said vessel, drive mechanism for the carrier, a positively driven rotary element, transmission means between said element and the said drive mechanism, locking and unlocking means between said transmission means and said element, an auxiliary rotary element, 105 transmission devices between said elements, locking and unlocking means between said devices and the auxiliary element, raising and lowering means between the auxiliary element and the carrier-support, and starting 110 and stopping mechanism including means for controlling the operative and inoperative conditions of the respective locking and unlocking means.

2. In a match machine, the combination of 120 a splint carrier, a vessel below the path of the carrier, a movable carrier-support adjacent said vessel, drive mechanism for the carrier, a brake for said mechanism, a positively driven rotary element, transmission means 125 between said element and the drive mechanism, locking and unlocking means between said transmission means and said element, an auxiliary rotary element, transmission devices between said elements, locking and 130 unlocking means.

- unlocking means between said devices and the auxiliary element, raising and lowering means between the auxiliary element and the carrier-support, operating means between 5 the auxiliary element and the brake, and starting and stopping mechanism, including means for controlling the operative and inoperative conditions of the respective locking and unlocking means.
- 10 3. In a match machine, the combination of a splint carrier, a vessel below the path of the carrier, a movable carrier-support adjacent said vessel, drive mechanism for the carrier, a positively driven rotary element, 15 transmission means between said element and the said drive mechanism, locking and unlocking means between said transmission means and said element, an auxiliary rotary element, transmission devices between said 20 elements, said devices including a wheel loosely mounted on the auxiliary element, locking and unlocking means for said wheel, raising and lowering means between the auxiliary element and the carrier-support, 25 and starting and stopping mechanism, including means for controlling the operative and inoperative conditions of the respective locking and unlocking means.
4. In a match machine, the combination of 30 a splint carrier, a vessel below the path of the carrier, a movable carrier-support adjacent said vessel, drive mechanism for the carrier, a brake for said mechanism, a positively driven rotary element, transmission means 35 between said element and the said drive mechanism, locking and unlocking means between said transmission means and said element, an auxiliary rotary element, transmission devices between said elements, said 40 devices including a wheel loosely mounted on the auxiliary element, locking and unlocking means for said wheel, raising and lowering means between the auxiliary element and the carrier support, operating 45 means between the auxiliary element and the brake, and starting and stopping mechanism, including means for controlling the operative and inoperative conditions of the respective locking and unlocking means.
- 50 5. In a match machine, the combination of a splint carrier, a vessel below the path of the carrier, a movable carrier-support adjacent said vessel, drive mechanism for the carrier, a positively driven rotary element, 55 transmission means between said element and the said drive mechanism, locking and unlocking means between said transmission means and said element, an auxiliary rotary element, transmission devices between said 60 elements, said devices including a wheel loosely mounted on the auxiliary element, having a hub with a plurality of key-ways, a movable key having a member by actuation of which the key is moved to and from locking 65 relation with the hub, and a key-support on the auxiliary element, raising and lowering means between the auxiliary element and the carrier support, and starting and stopping mechanism, including means for periodically actuating said key member and 70 means for controlling the operative and inoperative conditions of the said locking and unlocking means.
6. In a match machine, the combination of a splint carrier, a vessel below the path of the carrier, a movable carrier-support adjacent said vessel, drive mechanism for the carrier, a brake for said mechanism, a positively driven rotary element, transmission means between said element and the said 75 drive mechanism, locking and unlocking means between said transmission means and said element, an auxiliary rotary element, transmission devices between said elements, said devices including a wheel loosely 80 mounted on the auxiliary element, having a hub with a plurality of internal ways, a movable key having a member by actuation of which the key is moved to and from operative relation with the hub, and a key-support 85 on the auxiliary element, raising and lowering means between the auxiliary element and the carrier-support, operating means between the auxiliary element and the brake, and starting and stopping mechanism, including means for periodically actuating said key and means for controlling the operative and inoperative conditions of the 90 said locking and unlocking means.
7. In a match machine, the combination of a splint carrier, a vessel below the path of the carrier, a movable carrier-support adjacent said vessel, drive mechanism for the carrier, a positively-driven shaft, transmission means between said shaft and the said 95 drive mechanism, locking and unlocking means between said transmission means and said shaft, an auxiliary shaft, transmission devices between said shafts, locking and unlocking means between said devices and the 100 auxiliary shaft, raising and lowering means between the auxiliary shaft and the carrier support, said last-named means including a rod and crank connection with the auxiliary 105 shaft, and starting and stopping mechanism including means for controlling the operative and inoperative conditions of the 110 respective locking and unlocking means.
8. In a match machine, the combination of a splint carrier, a vessel below the path of the carrier, a movable carrier-support adjacent said vessel, drive mechanism for the carrier, a brake for said mechanism, a positively driven shaft, transmission means between said shaft and the said drive mechanism, locking and unlocking means between said transmission means and said shaft, an auxiliary shaft, transmission devices between said shafts, locking and 115 unlocking means between said devices and the 120 auxiliary shaft, raising and lowering means between the auxiliary shaft and the carrier support, said last-named means including a rod and crank connection with the auxiliary shaft, and starting and stopping mechanism including means for controlling the operative and inoperative conditions of the 125 respective locking and unlocking means.
- 125

the auxiliary shaft, raising and lowering means between the auxiliary shaft and the carrier support, said last-named means including a rod and crank connection with the auxiliary shaft, brake operating means including a cam on the auxiliary shaft and a cam-actuated brake connection, and starting and stopping mechanism including means for controlling the operative and inoperative conditions of the respective locking and unlocking means.

9. In a match machine, the combination of a splint carrier, a vessel below the path of the carrier, a movable carrier-support adjacent said vessel, drive mechanism for the carrier, a positively driven rotary element, transmission means between said element and the said drive mechanism, locking and unlocking means between said transmission means and said element, an auxiliary rotary

element, transmission devices between said elements, said devices including a wheel loosely mounted on the auxiliary element having a hub with a plurality of key-ways, a movable key having an arm by actuation of which the key is moved into and from locking relation with the hub, and a key support on the auxiliary element, raising and lowering means between the auxiliary element and the carrier support, and starting and stopping mechanism, including two spaced abutment members movable into and from the rotary path of the key-actuating arm and means for controlling the operative and inoperative conditions of the said locking and unlocking means.

Signed at Barberton, in the county of Summit and State of Ohio, this 21st day of March, A. D. 1917.

WILLIAM ROBERTS.
